HEAT INSULATION

Richard E. Gould, Dayton, Ohio, assignor to General Motors Corporation, Dayton, Ohio, a corporation of Delaware

Application January 30, 1934, Serial No. 708,957

6 Claims. (Cl. 154—45)

This invention relates to refrigerating apparatus and more particularly to heat insulated cabinet constructions.

It has been found that sheets of a metallic heat reflecting material, such as bright aluminum foil, spaced by thin substantially dead air spaces, provides a very efficient form of insulation. However, the fabrication of such an insulation is a particularly troublesome problem. This is very important because of the fact that this type of insulation is in competition with other types of insulation, such as that of cellulose fiber loosely packed in a container, which are also relatively high in efficiency and low in price. In order to meet this competition, it is necessary that this foil insulation be either more efficient or lower in cost or both more efficient and lower in cost than competitive types.

It is an object of my invention to provide an insulating structure embodying sheets of heat reflecting material, such as bright aluminum foil, provided with thin substantially dead air spaces between the sheets which is at least as efficient and which can be readily and economically manufactured at a rapid rate and at a lower cost than other types of commercial insulation.

It is a further object of my invention to provide an insulating structure containing spaced sheets and having a more efficient and more economical means for supporting the sheets which includes rather heavy paper strips formed into generally tubular structures extending parallel with the plane of the sheets.

It is another object of my invention to form a light weight insulating structure including spaced parallel sheets with substantially dead air spaces therebetween which sheets are supported by a light weight resilient framework which may be compressed to a varying degree to vary the spacing of the sheets and the thickness of the insulating structure without material damage.

Further objects and advantages of the present invention will be apparent from the following description, reference being had to the accompanying drawings, wherein a preferred form of the present invention is clearly shown.

In the drawings:

Fig. 1 is a transverse vertical sectional view of a refrigerating cabinet and a refrigerating apparatus embodying my invention;

Fig. 2 is a perspective view of one of the insulating units shown within the walls of the cabinet in Fig. 1;

Fig. 3 is a transverse vertical sectional view

through a refrigerator cabinet showing a modified form of my invention;

Fig. 4 is a perspective view of one of the insulating units shown within the walls of the cabinet of Fig. 3;

Fig. 5 is a modified form of insulation unit for the cabinet shown in Fig. 1;

Fig. 6 is a sectional view along the line 6—6 of Fig. 5;

Fig. 7 is a sectional view along the line 7—7 of Fig. 2;

Fig. 8 is a sectional view along the line 8—8 of Fig. 2;

Fig. 9 is a sectional view along the line 9—9 of Fig. 4; and

Fig. 10 is a sectional view of another modification similar to Fig. 4.

Referring to the drawings and more particularly to Fig. 1, there is shown a compressor 20 for compressing the refrigerant and for forwarding the compressed refrigerant to a condenser 21 where the compressed refrigerant is liquefied and collected in a receiver 22. The liquid refrigerant is forwarded through a supply conduit 23 to a suitable expansion controlling device, such as a 25 restrictor 24, from which the refrigerant is conducted through a conduit 25 to an evaporator 26 located within the food compartment 27 of a refrigerator cabinet 28. The liquid refrigerant evaporates within the evaporator 26 under reduced pressure and is returned to the compressor through the return conduit 29. The compressor is driven by an electric motor 30 under the control of a snap acting switch means 31 which is operated by a thermostat 32 in contact with the 35 surfaces of the evaporator 26 and exposed to the air within the food compartment 27.

The food compartment 27 is provided with a sheet metal inner wall or inner liner 33 which has its front edge fastened and sealed to a rectangular frame 34 which surrounds the door opening. Within the door opening there is provided a suitable door 35 having an inner pan 36 formed of sheet metal fastened to a framework of treated wood 37 or other suitable material having a low 40 heat conductivity. Fastened to this framework 37 but separated from the inner pan 36 by the framework 37 is an outer sheet metal cover 38 which forms the outer face of the door. Between the inner pan 36 and the outer covering 38 45 there is provided a plurality of insulating units 39. Surrounding the food compartment 27 and the inner liner 33 are the outer sheet metal walls 40 which form the outer structure of the cabinet and which are also fastened to the framework 34 50 55

but which are spaced from the inner sheet metal walls or inner liner 33. Between the inner liner 33 and the outer sheet metal walls 40 are a plurality of insulating units similar to the insulating units 39 shown within the door structure and also designated by the reference character 39.

Referring now to Figs. 2, 7, and 8 for a more complete disclosure of the insulating units 39, there is shown an outer envelope or bag 42 formed of a waterproof paper such as sheet formed of a plurality of sheets of paper having a thin sheet of asphalt therebetween. This bag is sealed by suitable means, such as asphalt, in order to exclude external air and moisture from the insulating unit. Within this bag or waterproof enclosure 42 is a plurality of sheets designated by the reference character 43.

Referring now more particularly to Figs. 7 and 8 for a better disclosure of the sheets, there is shown a sheet of paper 44 having its opposite side or longitudinal edge portions turned back upon itself and curled to form the tubular structures 45 which are fastened by asphalt as at 46 in order to retain this form. Between the curled tubular edge portions of this sheet there is provided a sheet 47 of a heat reflecting material such as bright aluminum foil which is fastened to the sheet of paper 44 by a thin layer of asphalt 48. Extending at right angles to the tubular structure 45 there is provided at the end portions of the sheet, as well as at the center portions of the sheets, the tubular structures 50 formed of sheets or strips of heavy paper 51 each of which is turned back upon itself and fastened by asphalt at 52 so as to form a flat bottom portion with an integral flange portion 55 extending therefrom. These tubular structures 50 which extend along the edges of the sheets 43 at their ends and also across the center portion of the sheets, have their flat bottom portions and integral flange portions fastened to the sheets by thin layers of asphalt 54 so as to provide a tubular frame structure which is made a unit with the sheet and which extends around the edges of the sheet and 45 has a tubular stiffening member which extends across the central portion of the sheet.

These sheets, together with their tubular structures, are stacked together and within the envelope 42 and are held by being tightly packed 50 within this envelope 42. With this type of structure it is possible to curl and fasten the edges as well as apply the foil to the paper in a continuous machine and the transverse tubular structures may be fastened to the sheets on top of the foil 55 as the material leaves or is drawn from the machine. In this way the structure may be very rapidly and economically manufactured. The only material required is heavy paper, aluminum foil, asphalt, and a waterproof envelope. By manufacturing this insulating structure in this manner, its cost may be materially reduced.

Referring now to Fig. 3, there is disclosed a refrigerator cabinet 60 having an inner liner 61 formed of sheet metal which encloses a food compartment 62 for containing a cooling unit 63 for cooling the food compartment. The front of a food compartment is closed by a door 64 which is provided with an inner sheet metal member 65 and an outer sheet metal member 66 between which are provided a plurality of relatively small insulating units 67 of a standard size. Surrounding the inner sheet metal liner 61 but spaced therefrom are the outer sheet metal walls 68. Between the inner sheet metal liner or inner wall

61 of the cabinet and the outer walls 68, there is provided the standard insulating units 67 similar to the insulating unit 67 shown within the door. These insulating units 67 are preferably made of a standard size in the shape of a large brick so that they may be turned in one way or another in order to fit the insulating space. In this form, insulating units are all made of the same size to facilitate manufacture and the necessity for a number of different sizes of insulating structures 10 is avoided.

Referring now more particularly to Fig. 4, for the details of the insulating units 67, there is shown a sealed envelope or waterproof enclosure 69, which contains a plurality of sheets 70 each 15 of which have the four edges thereof turned back upon itself and curled so as to form tubular structures generally designated by the reference character 71.

Referring now more particularly to Fig. 9, there is shown a section through one of these tubular structures showing the sheet 70 formed of a sheet of heavy paper 73 to which is fastened by asphalt or other adhesive a sheet of bright metallic foil 74 which, differently from the modification 25 shown in Figs. 1 and 2, extends coextensively with the sheet of paper 73. The edges of this sheet so assembled are turned back upon itself and curled and fastened by asphalt 75 to another portion of the sheet spaced from the edge to form the permanent tubular structures 71 at the edges of the sheet.

In Fig. 10 there is shown a modified form in which within the enclosure or envelope 80 there is provided sheets 81 formed of heavy paper 82 35 having a sheet of foil 83 fastened thereto and extending co-extensively therewith. The edges of each of the sheets are turned back upon the sheet and curled more than a single revolution in order to form relatively-stiff tubular structures 84 at the 40 edges of the sheets. By reason of the thickness and stiffness of the sheets, particularly because of the asphalt or other adhesive between the sheets, this tubular structure retains its tubular form and when placed within the water-proof envelope or bag 80 is further prevented from unwinding by being tightly confined therein.

Referring now more particularly to Fig. 5, there is shown a modification of the insulating structures shown in Figs. 1 and 2, which modification 50 is generally designated by the reference character 90. In this modification a sealed outer envelope 91 of waterproof paper, or other suitable material, is provided. Packed tightly within this envelope is a plurality of sheet and frame 55 structures 92 having a framework 93 formed of relatively narrow strips of paper 94 turned back upon themselves and fastened by asphalt 95 in order to form generally tubular structures with flat bottoms and integral flange portions. These 60 tubular structures with the flat bottoms are preferably fastened to a sheet of bright aluminum heat reflecting foil 96 by a suitable adhesive, such as hot asphalt 97. These tubular structures 93 extend along longitudinal edges of the sheet as 65 well as transversely across the end portions and the center portion of the sheet to form a rigid structure embodying a generally tubular framework fastened to the sheet of foil. The tubular structures 93 which extend across the end and 70 center portions of the sheet of foil 96 are fastened to the sheet of foil 96 and overlap the projecting flange portions 99 of the tubular structures extending along the side portions of the sheets and fastened thereto by a suitable adhesive such as 75

asphalt, generally designated by the reference character 98.

With this structure the tubular paper framework is provided only at the edge portions of the heat reflecting sheet so that both sides of the heat reflecting sheet are left uncovered in order to reduce the amount of paper required and to get the benefit of the reflecting properties of both sides of the sheet of foil. If desired, the alternate sheets of foil may be replaced by paper sheets in order to reduce the cost. This permits each air space to have one heat reflecting surface to reduce radiation. By having the transverse tubular members fastened to the flange portion 99 of the side tubular members a very rigid tubular frame structure is provided. These sheets and frame structures are stacked on top of one another and tightly packed within the envelope so that the sheets are held between the tubular structures and each reinforces the other. The light tubular frames which are formed of paper prevent any substantial amount of heat leakage by direct conduction from one of the foil sheets to the other and in this way increase the efficiency 25 of the foil type of insulation. This construction also reduces the weight of the insulation and thereby permits a reduction in the weight of the cabinet which renders it more easily movable.

This form may also be readily manufactured automatically by a suitable machine wherein the tubular structures are formed automatically and are fastened by the machine to the foil at a rapid rate. The tubular sections are resilient and compressible and in order to obtain a closer spacing 35 of the sheets to fit the insulation space the entire unit may be compressed. In this way a single standard tubular section may be used for different thicknesses of air spaces and insulation spaces.

In this way I have provided a refrigerator and insulation therefor which is more efficient, lighter in weight, and lower in cost.

While the form of embodiment of the invention as herein disclosed constitutes a preferred form, it is to be understood that other forms 45 might be adopted, all coming within the scope of the claims which follow.

What is claimed is as follows:

1. An insulating structure including a plurality of slab-like members each formed of a polygon shaped sheet portion having a plurality of edge portions forming its perimeter, each of the edge portions forming the perimeter of said polygon sheet portion being provided with a tubular structure extending along and adjacent it, the axes of each of said tubular structures extending along and parallel to the adjacent edge

portion of the perimeter, a plurality of said slab-like members being stacked one upon the other and grouped together to form an insulating unit.

2. An insulating structure including slab-like members each formed of a polygon shaped sheet portion having a plurality of edge portions forming its perimeter, a tubular structure for each of said edge portions, each of said tubular structures extending along and having its axis parallel to its adjacent edge portion, the axes of all said tubular structures being located upon one side of the plane of its sheet portion, a plurality of said slab-like members being grouped together to form an insulating unit.

3. An insulating element of the kind described comprising a rectangular sheet of highly flexible material, single hollow elastic members extending lengthwise of the respective edges of said sheet in upright relation to a surface thereof to constitute an elastic frame for resiliently spacing 15 said sheet from an adjacent sheet to form a dead air space bounded by said frame, and flanges forming parts of said members whereby the latter are secured directly to said surface of said sheet.

4. An insulating element of the kind described comprising a rectangular unitary sheet of flexible material, single hollow elastic members secured to a surface of said sheet and extending along opposite end edges thereof, and additional single hollow elastic members secured to said surface 20 of the sheet and extending along opposite longitudinal edges thereof between and in engagement with said first named hollow members, said hollow members together constituting an elastic rectangular frame in perpendicular relation to 25 said sheet for maintaining the latter in a flat condition and for resiliently spacing said sheet from an adjacent element to form a dead air space bounded by said frame.

5. An insulating element comprising a polygonal sheet of material, some of the edge portions of the polygonal sheet being formed to provide single hollow spacing formations extending lengthwise along some edges of the sheet in upright relation with respect to the surface of said sheet to constitute spacing means for spacing said sheet from an adjacent sheet.

6. An insulating element comprising a polygonal sheet of material, some of the edge portions of the polygonal sheet being turned back upon the sheet and fastened to the sheet, said turned back portion having such a shape as to form hollow generally tubular spacing formations extending lengthwise along some edges of the sheet to constitute spacing means for spacing said sheet from 55 an adjacent sheet.

RICHARD E. GOULD.
